(57) **CLAIM**

I claim the ornamental design for a footwear cover, as shown and described.

DESCRIPTION

FIG. 1 is a front perspective view of a footwear cover of the present invention;

FIG. 2 is a rear perspective view of the footwear cover of the present invention;

FIG. 3 is a side elevational view of the footwear cover of the present invention;

FIG. 4 is a top plan view of the footwear cover of the present invention;

FIG. 5 is a bottom plan view of the footwear cover of the present invention; and,

FIG. 6 is a side cross-sectional view of the footwear cover of the present invention, taken at line VI-VI of FIG. 4.

The broken lines in the drawings are directed to environment and are for illustrative purposes only; the broken lines form no part of the claimed design.

1 Claim, 5 Drawing Sheets
